*Primary Examiner—B. J. Bullock**Assistant Examiner—Mitchell Siegel**Attorney, Agent, or Firm—S. Michael Bender***[57]****CLAIM**

The ornamental design for a protective covering for garage door springs, as shown and described.

DESCRIPTION

FIG. 1 is a front elevational view of the protective covering for garage door springs showing my new design;

FIG. 2 is a rear elevational view thereof;

FIG. 3 is an enlarged left end view thereof;

FIG. 4 is a right end view of FIG. 3;

FIG. 5 is a top plan view of FIG. 1;

FIG. 6 is a bottom plan view of FIG. 1; and,

FIG. 7 is a perspective view of FIG. 1.

The broken line showing of a spring in FIG. 7 is for illustrative purposes only and forms no part of the claimed design.

*FIG. 1**FIG. 2**FIG. 3*
